UNITED STATES PATENT OFFICE

1,998,191

SACK-LOADING DEVICE

Miles R. Frankenfield, Freeport, Ill.

Application December 7, 1934, Serial No. 756,548

8 Claims. (Cl. 226—59)

This invention relates to mechanism for facilitating the loading of heavy bulky material into bags or the like; and more particularly to a device for loading potatoes and similar goods into paper bags of the desired size from a larger container.

The primary object of the invention is to provide improved means for holding sacks during a loading operation and particularly means for spreading the open top of the paper bag and holding it open during a loading operation.

The invention is illustrated in a preferred embodiment in the accompanying drawings, in which—

Fig. 1 is a front elevational view of a device embodying the invention showing the front door of the casing open and the loading hopper tilted back out of operative position; Fig. 2 is a plan view of the same with the casing closed and the hopper in loading position; Fig. 3 is a side elevational view of the device in the position shown in Fig. 1; Fig. 4 is a sectional view taken as indicated at line 4 in Fig. 2; and Fig. 5 is a modification showing the casing door and hopper linked together so that the two will open and close simultaneously.

In the embodiment illustrated A designates a casing provided with a drop door A' and upstanding partition walls A²; B an open bottom hopper hinged to the casing A; and C spreader-means for opening and holding the tops of the paper bags during a loading operation.

The casing A may be of any suitable construction preferably having an angle-iron frame 6 which is covered with galvanized iron sheeting 7. Preferably, the frame is provided with rearwardly extending horizontal supporting members 8 to prevent the device from overturning when the hopper is turned back.

The front wall of the casing A' is of similar construction and is hinged to the lower front portion of the casing as indicated at 9.

The hopper B may also be formed of galvanized iron or the like and preferably has an iron frame 10 to provide strength without greatly increasing the weight. The hopper is journaled on the upper rear portion of the casing by means of spring hinges 11, the springs helping to counterbalance the weight of the hopper. The hopper is provided with an open bottom and has a front flange 12 which is adapted to overlap the top 13 of the drop-door A' and to hold the same in closed position. The hopper is further provided on its lower side with depending flanges 12a in which is slidably mounted spreader-mechanism C. As

best shown in Figs. 1 and 2 the spreader mechanism comprises a pair of trombone-like slides 14 and 15 equipped at opposite ends with outwardly extending handles 16 and 17. As shown in Fig. 4 the slides may be in the form of half-rounds and both of the slides impale the spreader-members 18. Alternate spreader-members are connected to the slide 14 by means of set screws 19 and the remainder of the spreader-members are rigidly connected to the slide member 15 by means of set screws 20. Thus it will be understood that if partially opened paper bags 21 are placed in the compartments 22, formed by the upstanding partition walls A², the hopper B, with the spreader-members in the position shown in Fig. 1 may be swung down into the position shown in Fig. 2 and the tops of the bags opened by moving the handles 16 and 17 outwardly. A bushel of potatoes or other merchandise may then be dumped into the hopper and distributed evenly between the bags in the various compartments without danger of breaking the bags or overloading the same. The hopper may then be tilted back, the door A' swung forwardly and the filled bags removed without difficulty. Usually each of the bags will contain within a few ounces of the weight of the merchandise in the companion bags.

In the modification shown in Fig. 5 the casing 25 is provided with a drop door 26, as above, and the hopper 27 which is hinged to the casing 25 at 28 has a downwardly projecting rigid arm 29 which is connected to the door 26 by means of a pitman 30. If desired, a lost-motion connection 31 may be provided between the arm 29 and the pitman 30 so that the drop door may be closed a little before the hopper swings into its exact loading position. The operation is the same as described above except that the door and hopper are opened and closed simultaneously.

The foregoing detailed description is given for clearness of understanding only, and no unnecessary limitations should be understood therefrom, but the appended claims should be construed as broadly as permissible, in view of the prior art.

I claim:

1. A device of the character set forth comprising: an open top casing adapted to confine a plurality of open-top paper bags of rectangular cross section; an open bottom hopper hinged to said casing in superposed position; and movable means on said hopper for simultaneously spreading open the tops of all of said bags and holding them open while the same are being filled from said hopper.

2. A device of the character set forth comprising: an open top casing having upwardly extending spaced walls forming a plurality of compartments, each of said compartments being adapted 5 to confine closely therein the side walls of an open-top bag; a hopper mounted on said loading chamber, said hopper having a bottom opening communicating with said compartments; and spreader-means for opening and retaining the 10 tops of said bags open in said compartments during a loading operation.
3. A device of the character set forth comprising: an open top casing having upwardly extending spaced walls forming a plurality of compartments, each of said compartments being adapted 15 to confine closely therein the side walls of an open-top bag; a hopper mounted on said loading chamber, said hopper having a bottom opening communicating with said compartments; and spreader-means on said hopper for opening the 20 tops of all the bags in said compartments simultaneously and holding them open during a loading operation.
4. A device as specified in claim 3, in which 25 the spreader-means comprises pairs of opposed spreader-members for each compartment, and means drawing said spreader-members against the side walls of each compartment.
5. A loading-device comprising: an open-top 30 casing having a plurality of upstanding partition-walls forming open-top compartments adapted to confine closely therein the side walls of open top paper bags; an open-bottom hopper hinged to said loading chamber; and spreader-members slidably mounted on the hopper near the bottom thereof and depending into said compartments, 5 said members being adapted to open said bags and hold them open during a loading operation.
6. A device as specified in claim 5, in which the front wall of the casing is in the form of a forwardly swinging drop-door and the hopper is 10 provided with a flange adapted to overlap said door and hold it in closed position.
7. Mechanism as specified in claim 5, in which alternate spreader-members are mounted on one trombone-like slide, and the remainder of the spreader-members are mounted on a similar companion slide, said slides being movable in opposite directions. 15
8. A loading device comprising: an open top casing having a forwardly movable drop-door hinged to the base of said casing, and a plurality of upstanding partition walls forming open-top compartments adapted to receive open paper bags; an open-bottom hopper hinged to said casing so as to swing rearwardly with respect to said door; movable means on said hopper for spreading open the tops of all the bags and holding them open during a loading operation; and link-means connecting said hopper and door so that both members will open and close simultaneously. 20
